W. L. GOLDSTON

FENCE WIRE CLAMP FOR FENCE STRETCHERS

Filed April 15, 1922

Fig. 1.

UNITED STATES PATENT OFFICE.

WILEY L. GOLDSTON, OF QUEBECK, TENNESSEE.

FENCE-WIRE CLAMP FOR FENCE STRETCHERS.

Application filed April 15, 1922. Serial No. 552,987.

To all whom it may concern:

Be it known that I, WILEY L. GOLDSTON, a citizen of the United States, residing at Quebec, in the county of White and State 5 of Tennessee, have invented certain new and useful Improvements in Fence-Wire Clamps for Fence Stretchers, of which the following is a specification, reference being had to the accompanying drawings.

10 In fence wire clamps for fence stretchers heretofore used the clamping members are constructed of metal and the jaws are therefore very likely to cut or weaken the wires of the fence to such an extent as to cause the 15 wires to eventually break. Furthermore in the clamps heretofore used there are no means for adjusting the hinge connections between the two clamp jaws therefore affording no way for taking up the slack, so 20 as to cause the jaws to properly cooperate for a firm clamping action on a wire. Also these former devices do not include means whereby the wire fence can be stretched more at the top than at the bottom and 25 vice versa, thereby preventing fence wire mesh from being properly hung on the post. when erecting a fence down or uphill, that is to say, where the incline starts.

It is, therefore, the purpose of this invention 30 to obviate these disadvantages, and yet at the same time to provide a clamp, which is very simple, efficient and practical in construction, and may be produced for a relatively low cost.

35 In the present construction of clamp, the opposite clamping members or jaws are constructed of suitable hard wood or similar material, which will enable the jaws to have a secure clamping action on the fence wire, 40 and yet at the same time will not injure the same to an extent that will cause it to eventually break.

Still another purpose is the provision of 45 hooks and eyes carried by the clamping members for hingedly connecting them, in combination with means whereby the hooks and eyes can be adjusted relatively to each other and to the jaws, not only to cause them to align perpendicularly, that is to say, where 50 they engage each other, but also for the purpose of taking up the slack, so that the jaws may come securely together, when clamping the fence wire.

55 A further purpose is the provision of opposed brackets on the clamping members, in which the ends of a chain are adjustable, so

that the top of the fence may be stretched more than the bottom of the fence and vice versa. To insure stretching the bottom of the fence greater than the top, the jaws are 60 provided with rings, to which a second chain can be connected, in order to create a greater pulling action on an end of the clamp, when erecting the fence uphill.

It is to be understood that the particulars 65 herein given are in no way limitative and that while still keeping within the scope of the invention, any desired modifications of detail and desired proportions may be made in the apparatus according to circumstances. 70

The invention comprises further features and combination of parts, as will be herein-after set forth, shown in the drawings and claimed.

In the drawings:—

75 Figure 1 is a view in perspective of the improved clamp constructed in accordance with the invention, and showing the same as connected to wire fence material, whereby it may be stretched;

Figure 2 is a cross sectional view on line 2—2 of Figure 1;

Figure 3 is an enlarged detail perspective view of one of the clamps with its jaws separated from the other;

Figure 4 is a view in elevation of the clamp, showing how the jaws are hingedly united.

Referring to the drawings, 1 and 2 designate 90 a pair of clamp jaws, which are substantially identical in construction. Each jaw comprises an elongated angle bar or member, which may be any suitable length or thickness, and constructed of any suitable material, preferably hard wood. One 95 face of each jaw is provided with a channel or rabbet 3, and passing through the outer flange of one jaw and arranged in superimposed positions are eye-bolts 4, there being 100 nuts 5 upon the opposite ends of the bolts, for the purpose of holding and adjusting them in place. The eyes 6 of the bolts are designed to be axially aligned.

A plurality of hook bolts pass through the outer flange of the other jaw, and mounted 105 upon these bolts 7 are nuts 8, which are designed for the purpose of adjusting the bolts and holding them in position. The hooks 9 of the bolts are also axially aligned, so as to enter the eyes 6 of the other bolts, in order 110 to hingedly connect the two jaws. It will be noted that by imparting a longitudinal

movement to the jaws in opposite directions, they may be separated, and on a similar reverse movement, they may be again hingedly connected. It will be noted that when 5 clamping fence wire mesh work, the eye and hook bolts pass through the wire mesh work, thereby additionally holding the mesh work in position and preventing it from being pulled from between the jaws.

10 Bolted to the remote side faces of the jaws by certain of the eye and hook bolts are bracket plates 10, which are U-shaped. The vertical portions of these bracket plates are positioned beyond the rear faces of the jaws 15 and terminate in flanges 11, which extend laterally toward each other, for the purpose of strengthening the vertical portions of the bracket plates. The vertical portions of the bracket plates are provided with 20 notches 12, and engaging corresponding opposite notches are rings 13, which are carried by the opposite ends of the chain 14. This chain 14 may connect to any suitable pulling or operating means, for instance 25 such as a lever illustrated in Figure 1, or by means of a pull block (not shown), whereby a pulling action may be imparted to the chain. The greater the pulling action on the chain the more secure the jaws will engage 30 the fence wire mesh work, and the tighter the mesh work may be drawn. The rings at the ends of the chain may engage with the notches, so that the top of the fence may be stretched more than the bottom of the 35 fence and vice versa.

Secured to the remote side faces of the jaws adjacent their lower ends by the lowermost hook and eye bolts are plates 15 having eyes 16, in which rings 17 are mounted. 40 An additional chain 18 may be connected to the rings 17, so that by attaching the chain to any suitable pulling or operating means, the lower part of the fence may be stretched

considerably greater than the upper part of the fence, when it is desired to erect a fence 45 on an incline or the side of a hill. Instead of connecting the chains 14 and 18 to the rings 13 and 17 in the manner shown, a single chain (not shown) may be made in a 50 loop at one end, said loop to engage the rings 13 and 17 of each jaw, whereby upon attaching a pulling device to the single end of the chain, the jaws may be drawn together, and the fence stretched, equally as well as with two chains. It is obvious that a double 55 chain (not shown) may be used to be connected to the rings for stretching the fence, and causing the clamping action of the jaws.

One of the advantages of this clamp is that in putting it on and taking it off the 60 fence, there are no nuts to take off or put on. The hooks and eyes slip together without any trouble.

Similar rings to those at the bottom of the clamp may be arranged adjacent the top of 65 the clamp, for urging a greater pulling action on the top of the fence than at the bottom.

The invention having been set forth, what 70 is claimed is:—

A wire stretcher clamp comprising a pair of elongated rigid clamping jaws rearwardly extending U-shaped brackets fixed to the outer sides of the jaws midway between the ends thereof and embodying relatively long central portions extending parallel with the jaws and having notches 75 in their inner edges, and rings releasably engageable in desired ones of said notches and constructed for connection with a pulling mechanism whereby the pulling stress may be exerted in a plane at either side of the transverse center of the clamp.

In testimony whereof I hereunto affix my 80 signature.

WILEY L. GOLDSTON.
